UNITED STATES PATENT OFFICE.

WALTER J. HARKIN, OF SEATTLE, WASHINGTON.

INTERNAL-COMBUSTION ENGINE.

1,151,178.

Specification of Letters Patent. Patented Aug. 24, 1915.

Application filed July 13, 1912. Serial No. 709,241.

To all whom it may concern:

Be it known that I, WALTER J. HARKIN, a citizen of the United States, residing at Seattle, in the county of King and State of Washington, have invented a certain new and useful Improvement in Internal-Combustion Engines, of which the following is a specification.

My invention relates to improvements in engines of the internal-combustion type, and the object of my improvement is to provide an internal-combustion engine that shall be adapted, first, for its operation, to utilize the inherent energy of any one of many kinds of combustible fluids, as for instance, gasoline, kerosene, coal gas, alcohol and the like; second, directly to rotate its main shaft in either direction, as may be desired, and to have the direction of such rotation changed at will; third, to cause its pistons with each revolution of its main shaft to transmit power to such shaft, and fourth, to operate with high efficiency; and a further object of my improvement is to provide an engine of such type that shall be simple in its plan of construction and reliable in its operation.

I attain these objects by devices illustrated or indicated in the accompanying drawings, in which—

Figure 1 is a view in side elevation showing some parts thereof in vertical-mid-section, Fig. 2 is a view on a larger scale of a part of my invention in similar vertical-mid-section as shown in Fig. 1, Fig. 3 is a view in vertical-section, of like parts of my invention shown in Fig. 2, but on a line at a right angle to the section line of such Fig. 2 whereby may be seen certain parts in different relative positions, Fig. 4 is a view in horizontal section on broken line $x-x$ of Fig. 2 of one part of the structure shown in said Fig. 2 and Fig. 5 is a view in horizontal section on broken line $y-y$ of Fig. 2, of the same part illustrated in Fig. 4.

Like reference numerals indicate like parts throughout the drawings.

Referring to the drawings, Fig. 1 illustrates my invention as embodied in a two-cylinder internal-combustion engine wherein a bed-plate 8 serves to support the bearings 9, within which a crank-shaft 10 is mounted to revolve and further serves to support the four columns 11 which are indicated by a fragmentary view, their upper portion being broken away. These four columns 11 are for supporting on their upper ends the two

cylinders, 12 and 13 respectively, together with the compression chamber 14, which is associated with the cylinder 12, and the compression chamber 15 which is associated with the cylinder 13; but I have not shown the obvious manner in which such cylinders and compression chambers may be secured to the tops of the columns 11.

Each of the cylinders 12 and 13 and the compression chambers 14 and 15 are provided, within their walls, with water jacket spaces 16 after a plan well known. The compression chamber 14 and the compression chamber 15 are each bored vertically throughout their length to form a cylindrical space 17. Within the space 17 of the compression chamber 14 is disposed to move reciprocally up and down a piston rod 18 upon the upper end of which is secured a piston 19 and at a suitable distance beneath such piston 19 is secured, on the same piston rod 18, another piston 20 of much greater length, as shown, and likewise within the space 17 of the compression chamber 15 is disposed a like piston rod 21 upon which is mounted a short piston 22 and a longer piston 23; all the pistons of both compression chambers 14 and 15 being provided with suitable packing rings of well known type as indicated in Fig. 1.

The upper ends of the cylinders 12 and 13 are provided with cylinder heads 24 each of which has a water jacket space 16 which by suitable passages not shown may communicate with the water jacket spaces 16 within the walls of its respective cylinder whereby a constant circulation of water for cooling purposes may be attained in a manner well known.

At the upper end of the cylinder 12 and extending through the walls thereof and thence through the walls of the compression chamber 14 and into the space 17, of the chamber 14, is a passage or port 25, and likewise a similar passage or port 26 extends between the space 17 of the compression chamber 15 and the boring of the cylinder 13 at the upper end of said cylinder 13. These ports 25 and 26, respectively, serve to admit an explosive mixture from the spaces 17 into their respective cylinders 12 and 13 and also permit the escape or exhaust, at the proper time, of the products of combustion from the cylinders 12 and 13 through the upper open ends of the cylindrical spaces 17.

Within the boring of the cylinder 12 is

disposed a piston 27 provided with suitable packing rings of well known type and such piston 27 is fixed upon a vertical piston rod 28 which extends downwardly through the bottom end of said cylinder 12 to connect in a well known manner with a connecting rod 29 which is articulated with the crank-shaft 10 in an obvious well known manner indicated in Fig. 1 while within the boring 10 of the cylinder 13 is a like piston 30 fixed on a piston rod 31 which in like manner is articulated with a connecting rod 32 that is associated also with the crank-shaft 10, but the association of the crank-shaft 10 with the connecting rods 29 and 32 is such that when the piston 27, in the operation of the engine, is uppermost in its reciprocal movement then the piston 30 will be lowermost in its extent of downward movement.

20 The piston rods 18 and 21 which are associated respectively with compression chambers 14 and 15 extend downwardly through and out of the bottom of their respective cylindrical spaces 17, as indicated 25 by fragmentary view in Fig. 1, to connect with eccentrics 33 and 34 respectively, each through the medium of a well known form of link-motion, not shown, such link-motion being interposed between the lower ends of 30 the fragmentary portions of the piston rods 18 and 21 and the upper ends of the fragmentary portions of the connecting rods 35 and 36, and 37 and 38 which pairs of connecting rods, respectively, connect with eccentrics 33 and 34. Thus in a well known way the relative positions of the pistons on piston rods 18 and 21 and the pistons 27 and 30 may be changed or reversed in a manner well known.

40 Disposed in the bottom of the cylinder 12, near the wall thereof, is an inlet puppet-valve 39 adapted normally to be maintained in a closed position by force of a spiral-spring 40 which surrounds its stem in a well known way and beneath the disk of the valve 39 is a pocket 41 into which outside air may freely pass through an opening indicated by a circle made by a dotted line, thus if the piston 27 be raised from the 45 bottom of the cylinder 12, thereby causing a tendency to form a vacuum beneath said piston 27, then atmospheric pressure will raise the puppet-valve 39 and outside air will rush into and through the pocket 41 50 into the cylinder 12.

55 A like inlet puppet-valve 42 provided with a like spiral-spring 43 is disposed in a like manner in the bottom of the cylinder 13 which is provided with a like pocket 44, which puppet-valve 42 is adapted to act in the same manner and for the same purpose as does the puppet-valve 39.

60 In the bottom of the cylinders 12 and 13, disposed respectively on the side opposite the inlet puppet-valves 39 and 42, are out-

let puppet-valves 45 and 46 of well known form which are normally maintained in a closed position by the spiral-springs 47 and 48 respectively. Beneath the disks of these outlet puppet-valves 45 and 46 are pockets 50 and 51 respectively each of which is provided with an opening in one of its sides which communicates with a pipe 49. Beneath each of the pockets 50 and 51 is a sub-pocket 52 and a sub-pocket 53 respectively into each of which extends the respective one of the valve stems of the outlet puppet-valves 45 and 46, and the holes 54 and 55 in the partitions between said pockets 50 and 51 and the sub-pockets 52 and 53 respectively insure an equal pressure in both of the sub-pockets 52 and 53 and both of the pockets 50 and 51 whereby there can be no tendency of air to leak between the valve stems and walls of their sockets. Thus a downward movement of the piston 27 may serve to close the inlet puppet-valve 39 and to force the air contents of the cylinder 12 into the pipe 49 by opening the valve 45 while a like downward movement of the piston 30 would serve to close the inlet puppet-valve 42 and to force the air contents of the cylinder 13 into the pipe 49 by opening the outlet puppet-valve 46, thus the reciprocal movements of the pistons 27 and 30 may 85 pump air into the pipe 49.

Extending upwardly from the central portion of the pipe 49 and connected therewith is a vertical pipe 56 leading to and connecting with a cross pipe 57. One end of this cross pipe 57 is connected with and leads into an opening 58 in the wall of the compression chamber 14 while the other end of said cross pipe 57 is connected likewise through an opening 59 into the compression chamber 15. Thus when the top of the piston 23 is lower than the opening 59 compressed air or gases from the pipe 50 may find passageway into the cylindrical space 17 between the piston 23 and the piston 22 to fill such space with air or other gas at a pressure equal to the pressure of such gas or air in the pipes 49, 56 and 57 and when such space is filled at such pressure an upward movement of pistons 23 and 22 will close the opening 59 and, such movement continuing, such compressed gas or air will be carried upward until the lower side of the piston 22 reaches or passes the lower edge of the port 26 of the cylinder 13 whereupon the compressed gas or air carried within the space between the pistons 22 and 23 may find passage and force its way into the cylinder 13. Obviously a like operation may be effected by the pistons 19 and 20 110 acting in conjunction with the openings 58 and 25.

When the piston 30 in the cylinder 13 reaches a desired point in the lower part of the cylinder 13 the piston 22 may be timed 130

in its movement by adjustment of the eccentrics 34 and the link-motion, not shown, so that its downward movement will cause its upper edge to fall lower than the top edge 5 of the opening 26 thus permitting the exhaustion of the space within the cylinder 13 above the piston 30, outwardly through the port 26 thence upwardly out of the open top of the cylindrical space 17, and likewise the 10 co-action of the pistons 27, 19 and 20, the eccentrics 33 and the link-motion, not shown, will serve to effect a like operation.

In Fig. 1 I have not shown means for supplying an engine with combustible fluids 15 or means for igniting such fluids but such means are illustrated in Fig. 2 wherein is shown by an enlarged but similar view in vertical mid-section a compression chamber similar to the compression chamber 14 of 20 Fig. 1.

Referring to Fig. 2 a spark-plug 60 is disposed in the wall of the cylinder 14 in a position within a hole extending through such wall whereby an explosive mixture 25 within the space 17 may be exposed to the action of an electric spark passing between the electrodes of such spark-plug 60. I have shown the vertical position of said spark-plug 60 as being such that upon the upward 30 movement of the pistons 19 and 20 an explosive mixture that may be contained in the space between such pistons 19 and 20 might be ignited before the bottom side of the piston 19 may reach and pass the lower 35 edge of the port 25 to admit such explosive mixture into an adjacent cylinder, but such spark-plug 60, if desired, may be disposed at a point higher in the wall of the compression chamber 14 whereby there can be no ignition 40 of the explosive mixture within the space between the pistons 19 and 20 until it is raised to a point where it may be admitted into the port 25.

A combustible fluid for operating an engine 45 may be admitted to the compression chamber 14 and within the space between the pistons 19 and 20 by means of a hole 61 disposed in the wall of the compression chamber 14, just below the spark-plug 60, 50 into which hole 61 may lead a suitable pipe, not shown, that may conduct such combustible fluid from a convenient source of supply, as may be understood by reference to Fig. 2. When the bottom side of the 55 piston 19 in its upward movement reaches a point where the compressed gases may find access into the port 25 compressed air may not enter the space between the pistons 19 and 20 through the opening 58, to which one 60 end of the cross-pipe 57 is attached, since at such time the upper end of the piston 20 will have passed above such opening 58 to close it, and at such time combustible fluid may gain entrance through the hole 61 into 65 the space between the pistons 19 and 20

whereby such combustible fluid and the compressed air within such space may mix to form an explosive mixture in a manner well known. Obviously such combustible fluid would have to be forced to feed through the 70 hole 61 by a pressure greater than the maximum pressure of the compressed air within the space between the pistons 19 and 20. Further, it will be seen that when the piston 19 is high enough to admit an explosive mixture into the port 25 then the upper side of the piston 19 will be above the upper edge of the port 25 thus closing the opening at the top of the cylindrical space 17, as shown in Fig. 3, but when, in its downward movement, the piston 19 passes the point where its upper side is lower than the upper edge of the port 25 then the adjacent cylinder may exhaust through the port 25 into the cylindrical space 17 thence upwardly and 85 out of the top thereof.

Referring to Fig. 3 the water jacket spaces 16 are supplied with an inlet hole 62 and an outlet hole 63, said inlet hole 62 being adapted to connect with a pipe, not 90 shown, leading to a source of cold water while the hole 63 may connect with a suitable drain pipe, not shown.

Fig. 4 more clearly shows, by a cross-sectional view on broken line $x-x$ of Fig. 2, 95 the form of the port 25 which affords a passageway between the cylindrical space 17 and an adjacent cylinder which port 25 may serve both for admitting an explosive mixture into an adjacent cylinder and for an 100 exhaust port for such cylinder through which products of combustion, which have been utilized, may pass in their way to the open air through the top of the cylindrical space 17.

Fig. 5, by a view in cross-section on broken line $y-y$ of Fig. 2, shows more clearly the plan of construction of the opening 58 which opening 58 communicates with 110 an end of the cross-pipe 57.

Thus it is seen that my invention embodies a plan of construction whereby a body of compressed gas or gases adapted to form an explosive mixture may be moved by and within a suitable inclosure, which movement may be such with respect to an adjacent cylinder that devices associated with such cylinder and such inclosure may permit, at proper times, such explosive mixture to find passageway from such inclosure to 115 such cylinder.

In the operation of an engine embodying the form of my invention as hereinbefore described, it is manifest that the downward movements of the pistons 27 and 30 will maintain a compression of air in the pipes 49, 56 and 57 which compressed air at proper times, in response to the action of the motion communicated to the piston rods 18 and 21 by the eccentrics 33 and 34, will be admitted 125

respectively to the space between the pistons 19 and 20 and the pistons 22 and 23 when such air may mix with combustible fluid which is injected through holes 61 to form 5 an explosive mixture whereupon such explosive mixture may thence be admitted through the ports 25 and 26 respectively and thence into the upper ends of the cylinders 12 and 13 respectively to force their respective pistons 27 and 30 downwardly, in a manner well known, and when either of the pistons arrives at a desired lower point in its respective cylinder, the space above such piston may be exhausted into the open air 15 through its respective port 25 or 26 and the open end of the cylindrical space 17, the opening and closing of such ports 25 and 26 being regulated respectively by the movements of the pistons 19 and 22 in an obvious manner.

Manifestly any form of device for igniting the explosive mixture may be substituted for the spark-plug 60.

From the foregoing description it will be 25 seen that my invention may be embodied in an internal-combustion engine having one cylinder only or in an engine having a plurality of cylinders, as may be desired, and various modified forms of the essential parts 30 of my invention may be employed without departing from the spirit of my invention.

What I claim is:

1. In an internal combustion engine, the 35 combination with two cylinders each provided with an inlet port at one of its ends and with inlet and outlet puppet valves at its opposite end, cylindrical air chambers communicating with said ports, of a piston within each of said air chambers adapted to 40 move a body of air from one part to another

thereof, means for connecting said outlet valves with said cylindrical chambers, driving mechanism operatively associated with each of said pistons to cause the latter to move a body of air lengthwise within its cylindrical air chamber to a position that will permit such body of air to enter the adjacent one of said cylinders, and an air-compressing piston associated with each of said cylinders adapted to force air into said adjacent cylindrical air chamber. 45

2. In an internal combustion engine, the combination with an engine cylinder having a port at one end, of an inlet puppet valve disposed in its other end, an outlet puppet-valve also disposed in the latter end, a cylindrical chamber disposed adjacent to said engine cylinder to communicate with said port, movable means in said cylindrical chamber adapted to move a confined body of air in a lengthwise direction thereof to discharge said air into said port, air conducting means disposed to extend between said outlet puppet-valve and said cylindrical chamber to conduct air from said outlet puppet valve to a point in said cylindrical chamber where it may be confined by said movable means, and a piston disposed within said cylinder and adapted when moved in one direction to draw air through said inlet puppet valve, and when moved in the opposite direction to force air out of said cylinder through said outlet puppet valve. 55

In witness whereof, I, hereunto subscribe my name this fourth day of June A. D., 75 1912.

WALTER J. HARKIN.
